MEANS AND METHOD OF FEEDING TO
IMPACT CRUSHERS

Herbert J. Wock, Alhambra, Calif.

Application January 16, 1950, Serial No. 138,861

6 Claims. (Cl. 241—5)

1

This invention relates to an improved means and method of feeding material to be crushed to an impact crusher and may be considered as an improvement over the disclosure made in my copending application Serial No. 68,872, filed January 3, 1949.

Heretofore, in operating an impact crusher the material to be crushed has generally been fed into the path of the striking faces on the rotor of the crusher in a more or less continuous, steady stream, the intention being to have the striking faces cut off successive increments of the stream and by impact crush or pulverize the material. In such procedures a portion of the stream may be positioned opposite the center of the striking face at the instant of impact but succeeding rocks will be encountered by the striking face near its edge so that there will be glancing or foul blows. When such foul blows are struck, not only are the edges of the impact shoes on the rotor severely damaged but the crushing is imperfectly performed so that a substantial amount of the material that is fed to the rotor must be re-run through the crusher. It is desirable to feed the material to the rotor of the impact crusher in such a manner that all of the material at the instant of impact will be opposite the face of the impact shoes. In this manner severe wear of the impact shoes is avoided and as each piece of material that is to be crushed is squarely struck a crushing with maximum efficiency is obtainable.

In my copending application there is disclosed one method of separating the material to be crushed into spaced or isolated bunches which are consecutively thrown in timed relation to the rotor into the path of the impact shoes. In that application a bucket conveyor is employed wherein each bucket throws its contents into the path of the impact shoes in timed relation thereto. Such an arrangement, while satisfactory at relatively low speeds, is not adequate where the rotor is traveling at extremely high speeds wherein the speed of an impact shoe may be in the neighborhood of as high as 30,000 feet per minute. In many instances it is desirable to drive the rotor of the impact crusher at these extremely high speeds in order to secure the maximum pulverizing or crushing effect. However, when the rotor is traveling at such speed the time interval when successive hammers or impact shoes passing the point of ingress of the material to be crushed, becomes extremely small.

The present invention has for its object the provision of a method and means for feeding the

2

material to be crushed into the path of the hammers or impact shoes in the form of spaced bunches or clusters which can be thrown into the path of the hammers or impact shoes at the necessary velocity to reach an impact position between consecutive hammers and wherein each bunch or cluster can reach a substantially centered position with relation to the hammer so as to be squarely struck thereby without stragglers encountering the edges of the hammers or impact shoes thus having foul blows.

With the foregoing and other objects in view, which will be made manifest in the following detailed description and specifically pointed out in the appended claims, reference is had to the accompanying drawing for an illustrative embodiment of the invention, wherein the figure is a schematic sectional view through an impact crusher and the feed therefor embodying the present invention.

Referring to the accompanying drawings wherein similar reference characters designate similar parts throughout, the impact crusher shown consists of a rotor 10 on a shaft 11 driven in the direction indicated and carrying one or more hammers or impact shoes 12. These hammers or impact shoes are shown as being arranged on diametrically opposite sides of the rotor so that the rotor will be balanced although the number and arrangement of the hammers can be varied. A striking plate 13 is arranged adjacent the rotor and is adapted to have the material that is struck by the hammers thrown thereagainst. The crushed material finds egress from the housing 14 that encloses the impact crusher through an outlet 15.

The feed embodying the present invention consists of a conveyor belt 16 which carries the rock or other material that is to be crushed, indicated at 17, to a hopper 18 into which it is discharged. The rock may be fed into the hopper in any other suitable manner although it is preferable to feed it to the hopper at a substantially uniform rate. Below the hopper there is disposed a dividing drum, generally indicated at 19, and which is rotatable on a shaft 20. This dividing drum has a series of pockets 21 formed on its periphery each of which, during the rotation of the drum, is adapted to receive a small quantity or group of the rocks 17 that are to be crushed, consecutive groups being illustrated in two of the pockets and indicated at 17a and 17b. An endless belt 22 is trained over pulleys 23 and 24 adjacent the periphery of the dividing drum and serves to maintain the groups of rock 17a

and 17b in their respective pockets until it is desired to release or empty a group after it passes the lower pulley 24. The pulleys are urged in spaced relation by means of compression springs 25 to maintain the belt in taut condition and 5 pressed against the periphery of the drum 19. Below the dividing drum there are two spaced endless belts 26 and 27, the adjacent reaches of which cooperate to define a chute 28 leading down toward the rotor 10. This chute is adapted 10 to have the groups of rock, emptied from the pockets 21, consecutively dropped therethrough toward the rotor 10. The belt 26 is trained over pulleys 29 and 30 whereas the belt 27 is trained over pulleys 31 and 32. Belt tighteners 33 and 15 34 maintain these belts in taut condition. On the belt 27 there are spaced paddles 35 or gatherers which preferably have resilient facings, such as rubber facings, vulcanized thereto. The housing 36 which encloses the dividing drum 19 20 and the belts 26 and 27 and their respective pulleys is adjustably mounted with relation to the housing 14 for vertical adjustment relative to the rotor 10 such as by the adjusting screws 37. When the housing 36 is raised or lowered with 25 relation to the rotor 10 all of the contained structure is adjusted with relation to the rotor 10 therewith.

The mode of operation is substantially as follows: The rock 17 that is to be crushed is fed into the hopper 18 and passes therefrom into the pockets 21 in the divider drum thus being divided into spaced or isolated groups 17a and 17b. A brush or wiper 38 may wipe off any rock that tends to become deposited on the divisions between the pockets and pass it into the next succeeding pocket 21. When a pocket with its contained group of rock, indicated at 17b, passes beyond the lower pulley 24, this rock will fall by gravity from the pocket into the chute 28. In 30 so doing the group of rock will tend to string out in the chute, that is, those rocks of the group 17b that are first released from the pocket will be immediately accelerated by gravity in a downward direction. Rocks of the group 17b that are 35 subsequently released from the pocket will also be immediately accelerated by gravity but the commencement of their acceleration will be at a later instant of time. Consequently there will be 40 some stringing out of the group in the chute 28 whereafter it is desired that the group be gathered into a compact bunch or cluster and caused to enter the path of the hammers 12 at high velocity and in such compact condition. The paddles 35 on the belt 27 are driven at relatively high 45 velocity and one of these paddles immediately follows the descending group of rock in the chute 28. The velocity of the following paddles 35 is 50 higher than the velocity attained by the descending strung-out group of rock in the course of its short descent through the chute 28. Consequently, during the fall of the group of rock the paddle 35 will catch up with the stragglers and quickly 55 bring up the stragglers to the velocity of the paddle. The velocity of the paddle is such as to bring up all trailing rock to or above the velocity 60 attained by the leaders that were first emptied from the pocket 21. The paddle 35 having thus gathered or bunched the rock into a cluster of course continues in its downward direction at 65 the same constant velocity but the rock, having been brought to this velocity, is still subject to the same accelerating effect of gravity and consequently the bunch or cluster will drop or fall away from the paddle 35 and enter the path of 70 75 the

the hammers 12 at a high velocity and in a bunched condition. The bunch or cluster can be thus centered with relation to the on-coming hammer or impact shoe so that the entire bunch or cluster will be given a square blow and thrown violently in the direction of the breaker plate 13.

While in impact crushers of this type it would be possible to deliver a bunch or cluster of rock for impact by each hammer, I prefer to alternate or stagger the hits of the hammers on the rotor. Thus in a typical operation of the present feed I will have only every fifth hammer passing below the bottom of the chute 28 make a hit. In conforming to such practice the rotor 10 is rotated at high speed and after one hit has been made with one hammer four succeeding hammers will pass the bottom of the chute 28 without making a hit. The fifth succeeding hammer passing beneath the chutes will then make the next succeeding hit on a descending bunch or cluster of rock. With this arrangement the engineering design of a feed for impact crushers embodying the present invention can be highly simplified. Thus, if the length of the belt 27 is three times the circumference of the pulleys 31 and 32 so that there are three paddles 35 equally spaced along the length of the belt, one paddle 35 will have to descend in the chute 28 for each two and one-half revolutions of the rotor 10 and the pulleys 31 and 32 will have to make one revolution for each two and one-half revolutions of the rotor 10. The speed ratio between the pulleys 31 and 32 and the rotor 10 under these circumstances would have to be 2 to 5, that is, for every revolution of the pulleys 31 and 32 the rotor 10 would have to make two and one-half revolutions. The drum 19, having four pockets, would make one-fourth of a revolution for each revolution of the pulley 31 so that the speed ratio between the shaft 20 and the pulley 31 will be 1 to 4. Any type of drive that will maintain such speed ratios between the rotor 10, the pulleys for the belt 27 and the divider drum 19 may be employed. As typical, however, I have shown chain and sprocket drives between these elements for maintaining such speed ratios it being understood that the chain tightener for the chain between the rotor 10 and the pulley 32 adjusts itself whenever the upper housing 36 is adjusted by the adjustment 37 with relation to the lower housing. This adjustment at 37 permits the entire feed to be adjusted up and down with relation to the rotor 10 so that the bunch or cluster may be accurately centered with relation to the hammer at the instant of impact. The centering of the bunch or cluster does not necessarily have to be at the exact center of the hammer but it should be so arranged with relation to the hammer that all rocks of the bunch or cluster will be given a square blow by the hammer and foul blows eliminated. The exact location of the paddles 35 on the belt 27 is determined by calculation so that these paddles will follow an emptied group of rock and bring up the velocity of the stragglers to the velocity of the leaders in the course of the descent through the chute 28.

From the above described method and apparatus it will be appreciated that the improved feed for impact crushers is highly advantageous in that it first divides the material to be crushed into groups which are consecutively dropped into the chute 28 formed by the belts 26 and 27. The dropping of the group necessarily involves some stringing out of the group in the course of its fall through the chute. However, this strung-

out group is gathered by the paddles 35 in the course of its descent and brought together into a bunch or cluster having the velocity of the paddle 35. When the bunch or cluster is thus gathered and brought to this velocity accelerated downwardly by the force of gravity but remains in its bunched or collected condition. Although the rotor 10 may be rotating at very high speed the velocity at which the bunch or cluster can be thrown into the hammer path is adequate to position the bunch or cluster in the path of a succeeding hammer even though the time interval between two consecutive hammers is extremely short. As the bunch or cluster is thus delivered to the hammer path in a compact or clustered condition, an opportunity is afforded to hit the rocks of the bunch or cluster squarely without foul blows which would be present if there were stragglers.

Various changes may be made in the details of the construction without departing from the spirit and scope of the invention as defined by the appended claims.

I claim:

1. The method of feeding material to be crushed into a rotary impact crusher which consists of allowing the material to freely fall towards the crusher, then gathering the material into a bunch or cluster in the course of its fall, and then allowing the bunch or cluster to continue to fall toward the impact crusher.

2. The method of feeding material to be crushed into a rotary impact crusher which consists of dividing the material to be crushed into separated groups, allowing the groups to freely fall toward the crusher consecutively in timed relation to the crusher, gathering each group into a bunch or cluster in the course of its fall and bringing it up to a predetermined velocity towards the crusher and then allowing the bunched material to fall in bunched condition toward the crusher.

3. An impact crusher comprising a rotary crusher having one or more hammers thereon, means for dividing the material to be crushed into groups and allowing the groups to consecutively freely fall towards the crusher in timed relation thereto, and means for gathering the groups of material in the course of their falls toward the crusher into bunches or clusters and then allowing them to continue their free falls towards the crusher in timed relation thereto.

4. An impact crusher comprising a rotary crusher having one or more hammers thereon, opposed endless belts forming a chute leading downwardly toward the crusher, one of said belts having paddles thereon and being driven in timed relation to the crusher, and means for delivering the material to be crushed so as to fall freely between the belts in spaced groups so that the groups in the course of their fall may be picked up by the paddles and compacted into bunches or clusters and brought to a predetermined velocity toward the crusher.

5. An impact crusher comprising a rotary crusher having one or more hammers thereon, a pair of opposed endless belts providing a chute leading toward the crusher, one of the belts having paddles thereon and being driven in timed relation to the crusher, a divider drum having pockets arranged over the chute, means for supplying material to be crushed to the divider drum to be divided into groups in the pockets thereon, and means for rotating the divider drum in timed relation to the crusher, the divider drum being arranged to empty its pockets over the chute so that the contents of the pockets may fall freely through the chute.

6. An impact crusher comprising a rotary crusher having one or more hammers thereon, a pair of opposed endless belts providing a chute leading toward the crusher, one of the belts having paddles thereon and being driven in timed relation to the crusher, a divider drum having pockets arranged over the chute, means for supplying material to be crushed to the divider drum to be divided into groups in the pockets thereon, and means for rotating the divider drum in timed relation to the crusher, the divider drum being arranged to empty its pockets over the chute so that the material emptied therefrom may fall freely through the chute, the belts and divider drum being vertically adjustable with relation to the crusher.
